Des. 211,716
Patented July 23, 1968

211,716

WORKMAN'S UTILITY CART

Cleo B. Roloson, 22034 Crespi St.,
Woodland Hills, Calif. 91364

Filed July 17, 1967, Ser. No. 7,820

Term of patent 3½ years

(Cl. D14—3)

FIG. 1

FIG. 2

FIG. 3

FIG. 4

FIG. 5

FIG. 6

FIG. 7

FIGURE 1 is a perspective view of a workman's utility cart showing my new design;

FIGURE 2 is a front end view thereof;

FIGURE 3 is a side elevational view thereof;

FIGURE 4 is a rear end view thereof;

FIGURE 5 is a side elevational view thereof illustrating the side opposite to that shown in FIGURE 3;

FIGURE 6 is a bottom plan view thereof; and

FIGURE 7 is top plan view thereof.

I claim:

The ornamental design for a workman's utility cart, substantially as shown.
